UNITED STATES PATENT OFFICE

2,497,525

STARTER SWITCH SEASONING AND
TESTING APPARATUS

Leon H. Zyta, Cleveland Heights, Ohio, assignor
to General Electric Company, a corporation of
New York

Application July 9, 1947, Serial No. 759,785

8 Claims. (Cl. 175—183)

1

My invention relates to apparatus for aging and testing automatic starter switches for fluorescent and other discharge lamps and other electrical devices. Such starter switches perform a switching function upon being supplied with electrical energy to provide both starting and operating conditions to the electric device they control and are usually adapted to repeat the switching function until proper operation of said device occurs.

An object of my invention is to provide apparatus for testing the operation of automatically functioning starter switches of the type used with fluorescent lamps and other electrical devices. A further object is to provide apparatus for testing starter switches wherein a glow discharge in a confined atmosphere supplies the heat for actuating a bi-metal switching element. The apparatus is equally well adapted to test other types of starter switches, for instance, another type of starter switch which is caused to function by the effect of heat from a resistance member on a bi-metal switching element, and still another type which operates electro-magnetically.

Another object of my invention is to provide means in combination with testing apparatus for aging and seasoning starter switches wherein repeated operation of the starter switches is effected and abnormal electrical potential is applied during said aging and seasoning. Normally the starter switch is connected to a fluorescent lamp or other electrical device which starts to function after a short starting interval bringing about a change in the electrical potential applied to said starter switch so that it is no longer capable of being aged and seasoned.

Another object of my invention is to provide apparatus for testing starter switches wherein all conditions of improper operation are indicated. Unsatisfactory starter switches may have unusually low resistance (usually a short-circuited condition) or may have the proper resistance but be defective in several other ways so as not to be capable of operating within a desirable interval of time. The testing of all starter switches for unusually low resistance and capability of operation within a definitely limited time interval is an adequate testing procedure.

Other objects and advantages of my invention will appear from the following description of species thereof and from the accompanying drawing.

In the drawing, Fig. 1 is a side elevation of one species of aging and testing apparatus comprising my invention, said elevation being reduced in

2

height by the removal of an intermediate horizontal portion of uniform construction and having a vertical portion substantially equal to a quarter section broken therefrom; Fig. 2 is a plan view of the aging and testing apparatus from which is broken a portion overlying two of the heads thereof; Fig. 3 is a side elevation of a starter switch tested by the apparatus; Fig. 4 is a perspective view, partially in phantom, of the starter switch holder of each head; Fig. 5 is a schematic wiring diagram of one head, and the associate electrical apparatus connected thereto at the first test station of the apparatus; and Fig. 6 is a perspective view of a commutator constituting part of the apparatus.

The starter to be tested, and shown in Fig. 3, is of the well-known glow switch type comprising a sealed glass bulb 5 filled with an ionizable atmosphere like neon and containing a fixed wire electrode 6 and a deformable inverted U-shaped bimetallic strip electrode 7 connected to respective lead wires 8 and 9. Upon application of a suitable potential across the leads 8, 9 a glow discharge is formed between electrodes 6 and 7 which heats the bimetallic electrode 7 and causes it to bend into engagement with the electrode 6, thereby extinguishing the glow discharge so that the electrode 7 cools and again separates from electrode 6. For a further understanding of the construction and operation of the switch reference may be had, for example to Patent 2,329,134 to L. R. Peters which is assigned to the same assignee as the present invention.

Referring particularly to Figs. 1 and 2, the apparatus shown therein comprises a rotatable carrier or turret 10 mounted on a vertical axis and adapted, upon rotation, to advance starter switches 11 placed in holders 12 located about the lower periphery thereof through the various steps of the seasoning and testing operations. The holders 12 are mounted on a lower disc 13 which in combination with a corresponding upper disc 14 is joined to a rotatable center column 15 by the flanged hubs 16 and 17 and form the basic elements of the turret 10. The mounting for the turret 10 is provided, on the one hand, by the bushing 18, bearing 19 and the stationary base plate 20 which cooperate to hold the lower end of the center column 15; and, on the other hand, the nut 21, ball bearing 22, bushing 23, bearing 24 which cooperate to hold the upper end of the center column 15 and which are supported from said base plate 20 through three upstanding standards 25 and three connected

channel shaped bars 17 extending radially over said turret 1. The functions of the apparatus occurring with the rotation of the turret 1 are under the control of switching means arranged in groups of three completely enclosed switches 18, 19 and 20 mounted on the top surface of the disc 5 and associated with each holder 3. Each group of switches 18, 19 and 20, the associated holder 3 and still other apparatus make up a separate entity referred to herein as one of the heads of the apparatus. A commutator 21 mounted on the adjacent portion of the center column 6 provides the means of supplying electrical energy to all the heads during rotation of the turret 1 which rotation carries the switches 18, 19 and 20 into engagement with cams 22, 23 and 24 on a stationary ring 25 mounted on the channel bars 17 so as to effect the desired operation and circuit changes initiated by said switches 18, 19 and 20. The sole driving means (not shown) of the apparatus consists of an electric motor and such other means as are required to rotate the turret 1 at a uniform rate, preferably at one revolution per minute, and which effects the rotation through engagement with the disc 4, the center column 6 or other members of the apparatus in well-known manner.

The apparatus is preferably mounted on a table at which an operator may be seated. The operator inserts a starter switch 2 in each of the holders 3 of the apparatus in the course of their regular presentation at a loading station and subsequently removes the switch therefrom after the rotation of the turret 1 has advanced said starter switch 2 to an adjacent station or completely around the apparatus depending on the indications thereof. As shown in Figs. 1 and 2, the loading station appears at A where the holder 3, which is comprised of two complementary blocks 26 and 27 of insulation material joined by a metal strap 28 of spring material and carrying two metal contact shoes 29 and 30, is under the influence of the stationary cam rail 31 which keeps the blocks 26 and 27 more widely separated to allow the more ready entrance of the starter switch 2 therebetween. Block 27 is a stationary member of the combination since it is attached to the disc 4 by the screws 32-32 whereas the block 26 is supported solely by the metal strap 28 and is biased toward block 27 by the springing tendency of said metal strap 28 so as to take a position determined by the engagement of the screw 33 extending therefrom with the cam 31. In inserting the starter switch 2 into the holder 3, the operator first bends the leads 34 and 35 (Fig. 3) extending from one end thereof back along the sides of the starter switch 2 and then orients said starter switch 2 with respect to the holder 3 so that the insertion of said end into the opening formed by the contact shoes 29 and 30 causes said leads 34 and 35 to engage respective contact shoes 29 and 30. The insertion of the starter switch 2 into the holder 3 is limited by the seating of the end of said starter switch 2 upon a shoulder 36 in the contact shoes 29 and 30 and separates the blocks 26 and 27 still further so that the full closing force of the metal strap 28 is free to press the contact shoes 29 and 30 against the leads 34 and 35 of the starter switch 2. The advance of an empty holder 3 beyond station A by the rotation of the turret 1 carries the screw 33 beyond the extent of the cam 31 allowing the blocks 26 and 27 to move closer together thereby

restricting the insertion of a starter switch 2 therein.

The first of the succession of seasoning and testing functions of the apparatus occurs when the holder 3 is advanced beyond the loading station A and is initiated by the bringing of the spring contacts 37 and 38, located directly below said holder 3 on the bottom surface of the disc 4, into engagement with the stationary contacts 39 and 40 on the insulating block 41 on the surface of table 42. As indicated in the wiring diagram, Fig. 5, the spring contacts 37 and 38 are connected electrically to the contact shoes 29 and 30 of the holder 3 and their engagement with stationary contacts 39 and 40 results in the starter switch 2 being connected in a test circuit including the alarm bell 43 and the secondary of the transformer 44. The primary of the transformer 44 is connected to a line source of electrical energy 45 at all times so that an electrical potential is being applied to the starter switch 2 which, if properly manufactured, presents an open-circuit high-resistance condition and does not ring the alarm bell 43. The electrical potential applied to the starter switch 2 is not sufficient to effect operation thereof so that it is under test in an inoperative condition. Should a defective (short-circuited, for instance) starter switch 2 be contained in the holder 3 so that the circuit therethrough is of low resistance or complete (a condition occurring if the bimetal control element d thereof is improperly shaped) the alarm bell 43 rings and the operator immediately removes said defective starter switch 2 from the holder 3 so that further test and seasoning by the apparatus is eliminated.

The continued operation of the apparatus rotates the turret 1 so that the spring contacts 37 and 38 of the holder 3 pass beyond the stationary contacts 39 and 40 breaking the circuit to the test means of which said contacts 39 and 40 are a part. The rotation of the turret 1 also effects the start of the seasoning operation by bringing the control arm 46 of the switch 18, which is mounted directly over said holder 3, into engagement with the cam 22 so that said switch 18 is actuated. The switch 18 and the adjacent switches 19 and 20 which control electrical connections made to the starter switch 2 contained in the holder 3 are an enclosed type in general commercial use and have a movable control arm adapted to engage the end of a longitudinally movable control pin extending from the enclosure. Switch 18, for instance, has a control arm 46 pivoted on a pin extending from a plate 46a attached to one side of the enclosure and is actuated through downward pressure on the roller 46b on the end of the control arm 46 which pressure moves said control arm 46 so that it pushes the control pin 46c a short distance into the enclosure whereby said switch 18 is actuated. The particular switches illustrated are manufactured by the Microswitch Corporation of Freeport, Illinois. At the moment of operation of switch 18, the wired connections to the starter switch 2 provide a circuit from the contact shoe 30 through wire 47 to the condenser 48 and to the switch 19 which is influenced by cam 23 so that a circuit is made to wire 49; and a second circuit from contact shoe 29 through wire 50 to the condenser 48 and to the switch 20 which normally makes a circuit through wire 51 to the grounded output lead of the fluorescent lamp ballast 52. The actuation of switch 18 by the cam 22 at the start of the seasoning operation

connects wire 49 to the other output lead 53 of the fluorescent lamp ballast 52 and thereby applies the electrical potential of said secondary directly to the starter switch 2. The input leads 54 and 55 of the lamp ballast 52 are connected to the conducting rings 56 and 57 (Figs. 1, 5 and 6), respectively, of the commutator 21 and supply a constant source of electrical potential to said ballast 52 since brushes 58 and 59 (of the usual design) also connected to the line source of current 45 are constantly engaged therewith. The commutator rings 56 and 57 are mounted on an insulating body 60 held by the center column 6 of the apparatus so as to turn with the turret 1 whereas the brushes 58 and 59 are mounted on spindles 61 extending from a ring 62 of insulation held by a flange on the stationary bearing 15. The mounting for the fluorescent lamp ballasts 52 associated with each of the holders 3 about the turret 1 is provided in a series (only one being shown) of plates 63 held on collars 64 attached to the center column 6, which plates 63 are equidistantly located about said column 6 and each support a group of four lamp ballasts 52. The connection of the full output potential of the lamp ballast 52 to the starter switch 2 causes a glow discharge to build up within said switch 2 to heat the bimetal switching element d thereof to effect bending thereof. Upon inter-engagement of the electrodes d and c, the glow discharge within the starter switch 2 ceases and the bimetal element cools and bends in the reverse direction so that it breaks the circuit therethrough. The applied electrical potential can again start a discharge within the starter switch 2 to repeat the previous cycle of operation. These repeated cycles of operation effect the seasoning or aging of the starter switch 2 and usually take place many times during the presently described portion of the rotation of the turret 1 which continues during 180 degrees of movement and for a period of one-half minute, after which the control arm 46 of switch 18 moves beyond the end of cam 22 and said switch 18 resumes its normal position.

The circuit connections to the starter switch 2 following the seasoning and aging operations of the apparatus are like those in effect prior to said operations and are incomplete so that said starter switch 2 is inoperative and therefore cools. Such a condition exists for 60 degrees of rotation of the turret 1 which is ten seconds of time in the present instance during which time the starter switch 2 cools substantially to a more normal starting condition.

The succeeding step in the operation of the apparatus occurs when rotation of the turret 1 carries the control arm 65 of switch 19 from the end of cam 23 allowing said switch 19 to take a normal position, and the control arm 66 of switch 20 engages the cam 24 causing switch 20 to take an open position. These switch operations connect the starter switch 2 in the normal starting arrangement with the fluorescent lamp 67 which is mounted adjacent to the holder 3 on the commercial lamp sockets 68 and 69 which are, in turn, fastened to the turret discs 4 and 5 by the brackets 70. The circuit connections to the starter 2 and lamp 67 are then through the wire 47, switch 19 and wire 71 to the cathode 72 at one end of the lamp 67 and through wire 50 and wire 73 to the cathode 74 at the opposite end thereof. The circuit connections from the ballast 52 to the lamp 67 are through lead 53, switch 18 and wire 75 to cathode 72 and lead 51 and wire 76 to cathode 74.

With the making of these circuit connections, the starter switch 2 begins to function normally as an automatic starter for the fluorescent lamp 67. If the starter switch 2 is properly constructed, the fluorescent lamp 67 starts and a change in the circuit connections thereto is made before the test interval is completed, in the present instance, by the turret 1 turning 60 degrees further, when switches 19 and 20 are again actuated. Because of the rate of rotation of the turret 1, the test period is limited to 10 seconds, the interval within which an acceptable starter switch 2 is required to function.

The succeeding interval of movement of the holder 3 and the starter switch 2 completes the cycle of operation of the apparatus and presents said holder 3 and starter switch 2 at an unloading area B before the operation. The initial circuit connections are re-established at such times by operation of switches 19 and 20 by the passage of the cam 23 into engagement with the control arm 65 of switch 19 and passage of the control arm 66 of switch 20 from cam 24. This arrangement of the switches 19 and 20 establishes an incomplete circuit from wire 47 through switch 19 to wire 49 and the open terminal of switch 18 and causes wire 50 to be grounded and the cathode 74 to be shunted through switch 20 and lead 51. The remaining circuit connections to the fluorescent lamp 67 remain and continue to keep it operating if the starter switch 2 has operated satisfactorily in the test period. The operator has merely to look at the short section 77 of the lamp 67 which appears below the light shield 78 to determine if the starter switch 2 in the holder 3 being unloaded is acceptable and either saves or discards the starter switches 2 that are taken from holder 3 in front of lighted or unlighted lamps respectively. Only the short lower section 77 of the fluorescent lamps 67 in the apparatus are coated with fluorescent material so as to reduce considerably the annoying glare of light given off thereby as the apparatus operates.

What I claim as new and desire to secure by Letters Patent of the United States is:

1. Apparatus of the class described comprising in combination, a movable carrier, a head on said carrier including a holder for supporting and making electrical connections to a starter switch, said head having mounted thereon a discharge lamp, a ballast for said lamp, and switching means, means for connecting said ballast to a source of electrical energy during movement of said head, means to connect said lamp through contacts of said switching means and through said ballast across said source of electrical energy and means to also connect said starter switch through other contacts of said switching means across said lamp, and means mounted along the course of movement of said head for actuating said switching means to close the aforesaid contacts and connect said starter switch across said lamp and also connect said lamp through said ballast across said source of electrical energy whereby to initiate starting and operation of said lamp so as to indicate at a location farther along said course of movement by the operation of said lamp or failure thereof the operativeness or inoperativeness of said starter switch.
2. Apparatus of the class described comprising in combination, a movable carrier, a head on said carrier including a holder for supporting and making electrical connections to a starter switch, said head having mounted thereon a discharge lamp, a ballast for said lamp, and switching

means, means for connecting said ballast to a source of electrical energy during movement of said head, means to connect said lamp through contacts of said switching means and through said ballast across said source of electrical energy and means to also connect said starter switch through other contacts of said switching means across said lamp, and means mounted along the course of movement of said head for actuating said switching means to close the aforesaid contacts and connect said starter switch across said lamp and also connect said lamp through said ballast across said source of electrical energy and to then open the said other contacts to disconnect only the starter switch after a definite short predetermined time interval during which an acceptable starter switch should start the lamp whereby to initiate starting and operation of said lamp so as to indicate at a location farther along said course of movement by the operation of said lamp or failure thereof the operativeness or inoperativeness of said starter switch.

3. Apparatus of the class described comprising, in combination, a movable carrier, a head on said carrier including a holder for supporting and making electrical connections to a starter switch, said head having mounted thereon a discharge lamp, a ballast for said lamp, and switching means, means for connecting said lamp to said ballast across a source of electrical energy during movement of said head, means to connect said starter switch through said switching means across said lamp, and means mounted along the course of movement of said head for actuating said switching means to first connect said starter switch across said lamp and to then disconnect the starter switch after a definite short predetermined time interval during which an acceptable starter switch should start the lamp whereby to initiate starting and operation of said lamp so as to indicate at a location farther along said course of movement by the operation of said lamp or failure thereof the operativeness or inoperativeness of said starter switch.

4. Apparatus of the class described comprising, in combination, a movable carrier, a head on said carrier including a holder for supporting and making electrical connections to a starter switch, said head having mounted thereon a discharge lamp, a ballast for said lamp and plural switching means, means for connecting said ballast to a source of electrical energy during movement of said head, means to connect said starter switch through a first pair of contacts of said switching means directly through said ballast across the source of electrical energy, means to connect said lamp through a second pair of contacts of said switching means and through said ballast across said source of electrical energy, and means to connect said starter switch through a third pair of contacts of said switching means across said lamp, and means mounted along the course of movement of said head for actuating said switching means to first close said first pair of contacts and then open them after a short predetermined time interval during which the starter switch is connected directly through said ballast across the electrical energy source so as to be aged and seasoned, said last-named actuating means being arranged to then close the second and third pairs of contacts of said switching means to connect said starter switch across said lamp and also connect said lamp through said ballast across said electrical energy source and to then open the third pair of contacts to disconnect only the

starter switch after a definite short predetermined time interval during which an acceptable starter switch should start the lamp whereby to initiate starting and operation of said lamp so as to indicate at a location farther along said course of movement by the operation of said lamp or failure thereof the operativeness or inoperativeness of said starter switch.

5. Apparatus of the class described comprising in combination, a rotatable turret, a plurality of heads on said turret each including a holder for supporting and making electrical connections to a starter switch, each head also including a discharge lamp, a ballast for said lamp, and switching means, means for connecting the several ballasts to a source of electrical energy during rotation of the turret, means in each head to connect said lamp through contacts of said switching means and through said ballast across said source of electrical energy and means to also connect said starter switch through other contacts of said switching means across said lamp, and stationary cam means located adjacent the turret for actuating said switching means in each head to close the aforesaid contacts and connect said starter switch across said lamp and also connect said lamp through said ballast across said source of electrical energy whereby to initiate starting and operation of said lamp so as to indicate at a location farther along the course of movement of the head by the operation of said lamp or failure thereof the operativeness or inoperativeness of said starter switch.

6. Apparatus of the class described comprising in combination, a rotatable turret comprising upper and lower discs, a plurality of heads on said turret each including a holder on the lower disc for supporting and making electrical connections to a starter switch, each head also including a discharge lamp mounted on and between said discs, a ballast for said lamp, and switching means on the upper disc, means including a commutator on said turret for connecting the several ballasts to a source of electrical energy during rotation of the turret, means in each head to connect said lamp through contacts of said switching means and through said ballast across said source of electrical energy and means to also connect said starter switch through other contacts of said switching means across said lamp, and stationary cam means located over the upper disc for actuating said switching means in each head to close the aforesaid contacts and connect said starter switch across said lamp and also connect said lamp through said ballast across said source of electrical energy whereby to initiate starting and operation of said lamp so as to indicate at a location farther along the course of movement of the head by the operation of said lamp or failure thereof the operativeness or inoperativeness of said starter switch.

7. In apparatus for testing glow switches of the type described, the combination of a gaseous electric discharge lamp, ballast means for said lamp, and switching means, means to connect said lamp through contacts of said switching means to said ballast means across a source of electrical energy and means to connect a glow switch under test through other contacts of said switching means across said lamp, and means for automatically actuating said switching means to close both aforesaid contacts in an effort to start said lamp into operation and to then open the said other contacts to disconnect only the glow switch after a definite short predetermined time interval dur-

ing which an acceptable glow switch should start the lamp whereby to permit observation of the lamp after said time interval to determine whether it has been started.

8. In apparatus for testing glow switches of the type described, the combination of a gaseous electric discharge lamp, ballast means for said lamp, and switching means, means to connect a glow switch under test through a first pair of contacts of said switching means directly to said ballast means across a source of electrical energy, means to connect said lamp through a second pair of contacts of said switching means to said ballast means across said source of electrical energy and means to connect the glow switch through a third pair of contacts of said switching means across said lamp, and means for automatically actuating said switching means to first close the first pair of contacts to effect repeated operation and consequent seasoning of said glow switch and to

10

5 then close the second and third contacts in an effort to start said lamp into operation and to then open the said third pair of contacts to disconnect only the glow switch after a definite short predetermined time interval during which an acceptable glow switch should start the lamp whereby to permit observation of the lamp after said time interval to determine whether it has been started.
